3 Claims. (Cl. 80—7)

This invention relates to dies for a rotary die thread rolling machine which is of the generally known type having a rotary die provided with a thread form around its circumference and co-operating with a stationary die which is of segmental form and extends around part of the circumference of the rotary die and wherein a number of blanks are introduced one after another into the space between the rotary die and stationary die so that each blank is rolled through to the exist end of the stationary die and the thread is impressed upon the blank.

The rotary die machine has certain advantages over the other class of thread rolling machine which is generally termed a "flat die machine" in which blanks are rolled between a pair of flat dies, one being movable and the other being stationary but because of the relatively high cost of the rotary die, this latter machine must have a substantially higher output than the flat die machine in order to be a commercially feasible and economical proposition and this question of economics is bound up with the subject of wear of the dies.

For a reason which is explained hereinafter a rotary die machine which has a constant and uniform thread form around its circumference corresponding to the thread form of the stationary die can be used economically for producing certain types of screws (e.g. machine screws) because the machine can be arranged so that the wear on the rotary die is distributed uniformly around the circumference thereof. With a flat die machine when rolling any type of screw it is inevitable that the maximum wear on the dies occurs at the starting ends of the dies. However with a rotary die machine which has a constant and uniform thread form around its circumference there are a very large number of potential starting points so that blanks can be introduced at very small intervals with the result that their thread rolling paths will overlap and thus the wear on the rotary die is spread much more uniformly around the circumference and much longer die life will result.

For economic working of a rotary die machine it is therefore desirable to be able to roll large numbers of blanks for each revolution of the rotor so that localised die wear is eliminated and the full effective circumference of the die is utilised.

However, when a blank is rolled between dies which are formed so as to produce the required thread on the blank it is necessary that the form of the dies at the start of the rolling operation is such that the material of the blank is initially deformed at each thread position with comparatively little pressure and the die form must also be sharp enough to prevent "skidding" of the blank when it enters between the dies. In connection with this latter requirement it has been the practice to provide transverse serrations on the dies to prevent any skidding of the blank.

As the blank progresses along between the dies towards the finishing end the thread form on the dies gathers the upset material into the die groove to produce the required thread. Certain types of screws such as machine screws, have relatively sharp threads and are of relatively fine pitch such that the ribs on the die, which correspond to the root or core form of the screw, are of sharp section

2

and thus with this type of screw, the thread and groove forms of the die may be of constant section from the starting end to the finishing end because the section will be sufficiently sharp at the starting end to permit of the desired initial deforming of the material with comparative little pressure to be followed by progressive upsetting and gathering of the material as the blank progresses to the finishing end of the dies.

Hence, machine screws and similar screws having relatively sharp threads and of relatively fine pitch can be satisfactorily produced economically on a rotary die thread rolling machine because the form of the die can be constant around the whole of the circumference of the rotary die.

15 However, there is another type of screw having a different thread form which cannot be produced by thread rolling using a die of constant form from one end to the other and the type of screw under consideration here is that in which the convolutions of the threads are spaced apart by a substantial distance. Self-tapping screws which have a substantial length of flat core between adjacent thread convolutions are a good example of this type of screw which, for purposes of simplicity, I term "spaced thread type," where the grooves between adjacent threads is not of a "sharp" character. Screw nails, drive screws, drive nails and the like also come in this category, 20 as mentioned specifically hereinafter, and are included within the term "screws" used herein.

With this type of screw the corresponding form of the die will have a rib of flat-top, rounded, or other "non-sharp" section to produce the groove between the threads and it is not possible, even on a flat die machine, to produce such screws successfully using dies of constant cross-sectional form from end-to-end and it has been 30 found necessary to have a die of changing form such that at the starting end of the die the form of the rib is of a sharp V-section to produce the initial deforming of the material with relatively small pressure and this form changes progressively to the final required flat top or other non-sharp form at the finishing end of the die.

These spaced thread type of screws can be produced on a flat die machine using the appropriate dies of changing cross-section (as above described), and it is also possible to produce such screws on a rotary die machine by 40 dividing the circumference of the rotary die into an appropriate number of separate similar dies each of which was formed to the required changing cross-section but with this arrangement the blanks have to be feed-indexed between the dies so that a blank is presented at each of the starting positions of the sub-divided rotary die and this inevitably leads to localised wearing of the dies. The initial cost of such a non-uniform rotary die is very much higher than the cost of a rotary die of constant thread form throughout its circumference and because of the localised wear, the life of the non-uniform rotary die is considerably shorter than the life of the constant thread form rotary die, whilst, due to the necessity for feed indexing in the former, the output thereof is much lower than the output from the constant form rotary die.

It is therefore the object of the present invention to provide improvements in dies for rotary die thread rolling machines which will allow the production of the spaced thread type of screws economically on such machine allowing the maximum number of blanks to be fed in for each revolution of the die and making full use of the whole of the circumference of the rotary die to distribute die wear evenly around the circumference. The maximum number of blanks which can be fed in a revolution of the rotary die will of course depend upon the size of any enlarged head at the end of each blank as the blanks must be spaced apart a sufficient distance to prevent any overlap between the heads, and to ensure that a whole

number of lateral pitches is maintained between adjacent blanks.

According to the present invention I provide dies for a rotary die thread rolling machine for the production of spaced thread type of screws wherein the form of the stationary die changes gradually from a sharp, or relatively sharp, form at the starting end to ribs having flat-tops, round, or other non-sharp form at the finishing end and the rotary die has a die form which is uniform in cross-section around the whole of its circumference, the cross-sectional form of the rotary die being somewhat similar to the form at the finishing end of the stationary die but with the crest of each rib being interrupted to give the ribs a degree of sharpness sufficient to ensure that the material of the blank is initially deformed with comparatively little pressure, the form of the stationary die at the finishing end being the dominant form which dictates the ultimate form of the thread which is produced on the blank.

In order to enable a clear understanding of the invention, the following detailed description, which is given with reference to the accompanying drawings, also contains a description of certain thread rolling methods as used or proposed hitherto so that the essential distinctive features of the invention can be seen against the background of the prior art as it is known to me.

In the accompanying drawings, which are mainly of a diagrammatic nature:

FIGURE 1 shows two examples of "spaced-thread" type of screws.

FIGURE 2 shows a rotor in accordance with the invention.

FIGURES 3(a)–(e) show alternate forms of the section of the constant thread form as taken on the line 3–3 in FIGURE 2.

FIGURE 4 shows a preferred form of stator to be used in the method according to the invention along with the rotor of FIGURE 2.

FIGURE 5 shows sections of the thread form on the lines 5W–5W, 5X–5X, 5Y–5Y, and 5Z–5Z of FIGURE 4.

FIGURE 6 is an example of one form of point on a spaced-thread type of screw.

FIGURES 7 and 7A illustrate diagrammatically the section of the point-forming part of a rotor used in producing a pointed spaced-thread type of screw, FIGURE 7A being a section on line 7A–7A in FIGURE 7.

FIGURES 8, 8B, 8C and 8D illustrate diagrammatically the section of a stator to be used in conjunction with the rotor of FIGURE 7, FIGURES 8B, 8C and 8D being respectively sections on the lines 8B–8B, 8C–8C, 8D–8D, in FIGURE 8.

FIGURES 9(a) and (b) show sectioned examples of further articles of the spaced-thread type.

FIGURE 10 illustrates diagrammatically the form of a rotor for producing articles as shown in FIGURE 9 in accordance with the invention.

FIGURES 11(a) and (b) show enlarged sections on the line 11–11 (FIGURE 10) of the rotor thread form for producing the articles shown in FIGURES 9(a) and (b) respectively.

FIGURE 12 illustrates another type of spaced-thread article and the section of thread form on the rotor for producing such article in accordance with the invention.

Referring to the drawings, FIGURE 1 illustrates two examples of "spaced-thread" screws and it will be observed that in each there is a sharp, or relatively sharp, thread 10, the convolutions of which are spaced apart by the grooves 11.

FIGURE 2 indicates diagrammatically a rotor in accordance with the invention wherein the thread form of the die is uniform and constant throughout the circumference of the rotor. FIGURES 3(a) to (e), show examples of alternative forms which may be used for the section 3–3 of the die form on the rotor, it being ap-

preciated that whatever form is chosen this will be constant throughout the whole circumference of the rotor. These examples are also given to illustrate what is meant by the interruption of the crest of each rib to give it a degree of sharpness which will be sufficient to ensure, in cooperation with the opposed stator, the initial deforming of the metal of the blank under relatively small pressure.

Referring to FIGURE 3(a) the die form has ribs 21 separated by main grooves 22, and each rib 21 is somewhat similar to the form at the finishing end of the stator (the section Y–Y, Z–Z, FIGURE 5 is representative of the finishing end form of the stator as is mentioned hereinafter) but, the crest of the rib 21 is interrupted by a relatively shallow groove 23 which modifies the flat top form and so creates the required amount of sharpness.

FIGURES 3(b) and 3(c) show alternative forms for the groove 23 and in FIGURE 3(d) the groove 23 has a partially convex base giving the effect almost of two grooves. FIGURE 3(c) illustrates how, in some cases, more than one groove may be employed. In all cases the purpose of the one or more grooves is to interrupt the crest of the rib 21 to achieve the desired degree of sharpness. The actual formation chosen will be a matter of choice, in practice, depending upon the actual thread form which is being rolled on the blank and taking into account other factors such as the material and dimensions of the blank. A certain amount of trial and error may be required to achieve the best formation of rib 21 for any particular case.

A further consideration is that the form of "interruption" on the crest of the rib 21 must be such that it will not interfere with the final thread form on the screw and the die form at the finishing end of the stator must be the dominant form which dictates the final thread form on the screw, such as in FIGURE 1.

It has been found in practice that a groove or grooves 23, relatively shallow, as compared with the depth of the thread-forming groove 22, will not in any way interfere with the action of the rib form at the finishing end of the stator and this rib form maintains the overall control of the final gathering and positioning of the metal of the blank to give the desired flat bottom grooves 11 (see FIGURE 1).

In fact, tests so far carried out, show that screws produced using dies according to the invention have a better thread form than do those produced by conventional rolling dies because it has been recognized in the past that conventional thread rolling dies do not produce true flat-bottom grooves 11 on a screw (see FIGURE 1) but tend to produce a groove which has slight concavity. It has been observed that screws produced on dies according to the invention have grooves 11 which are more nearly true flat bottomed than hitherto and whilst the reason for this is not fully understood, it is clear that the presence of the groove or grooves 23 has some beneficial effect in controlling the flow of the metal of the blank to make it follow more faithfully the shape which is dictated by the die form at the finishing end of the stator.

Whilst the form of the stator may be the same as has been previously used in connection with a sub-divided rotary die it is preferred to use the improved form of stator which is illustrated in FIGURES 4 and 5.

In FIGURES 4 and 5 the sections W–W, X–X, Y–Y, and Z–Z depict the changing form of the die cross section from the starting end to the finishing end.

As will be observed at the finishing end of sections Y–Y to Z–Z, the form is similar to the finishing form in a conventional stator with flat-top ribs 24 separated by relatively deep grooves 25 but at the starting end of the stator instead of the sharp ribs there are provided ribs 26 which are almost of flat-top form except that the crest of each rib is interrupted by a relatively shallow groove 27 to give the rib the degree of sharpness required to ensure the initial deformation of the metal of the blank under rela-

tively small pressure. As will be appreciated, any of the alternative forms of interruption illustrated in FIGURE 3 may be used at this starting end of the stator die so as to provide the ribs 26 with the desired degree of sharpness.

As will be observed from the section X—X, the groove 27 or other form of interruption gradually decreases until at the commencement of the finishing end section Y—Y, the interruption 27 has disappeared and the rib merges into the full flat-top section 24.

Previously it has always been considered essential to provide some means to prevent skidding of the blank when it is first introduced between the dies and the practice adopted hitherto has been to provide transverse serrations across the face of the die over the starting portion thereof thus roughening the surface of the die and providing the necessary grip to prevent skidding of the blank. Although this has been an essential requirement it has always been regarded as undesirable owing to the fact that the presence of the serrations does create flaws in the finished thread form but hitherto there has been no satisfactory way of avoiding the requirement for serrations or some similar form of roughening at the starting end of the dies.

However with the improved form of stator die described above, it is found that serrations can be eliminated or substantially reduced as there is considerably much less danger for skidding of a blank when it is introduced between dies in which the stator die has the form above described.

The presence of a somewhat similar form of die on the rotor also enhances this effect and the elimination of serrations on dies further reduces the cost of manufacture and eliminates the possibility of any flaws occurring in the finished thread form of a screw.

FIGURE 6 illustrates a form of spaced-thread type screw having a pointed end 28 with the thread form continued down along this pointed end and in the production of pointed screws of this type in accordance with the invention, the rotor would need to be provided with a point-forming portion with also a point forming portion being provided on the stator and for this particular application, a rotor and stator as illustrated diagrammatically in FIGURES 7 and 8 may be used.

The stator depicted in FIGURE 8 has a point-forming portion which is of generally known form and as will be seen from sections B—B, C—C and D—D this point forming portion changes gradually in form from the relieved section at B—B to the pronounced rib form 29 at D—D which dictates the actual form of the point. It will be appreciated that in FIGURES 7 and 8 the thread form of the dies has not been illustrated in the sections.

The cooperating point-forming portion on the rotor of FIGURE 7 is of constant section throughout the circumference of the rotor and as illustrated in the section A—A this point-forming portion is substantially similar to the finishing section D—D on the stator having the projecting rib 30 which cooperates with the rib 29 on the stator to form a desired point.

FIGURE 9 depicts in cross-section two further forms of articles which come under the classification of "spaced-thread type" the one shown in FIGURE 9(a) being a section through a drive screw having sharp ribs 31 of large helix angle separated by grooves 32 each of which has a bottom having slight convexity. The article illustrated in FIGURE 9(b) is a drive nail having pronounced ribs 33 separated by relatively wide grooves 34 which have a pronounced concavity.

The form of rotor suitable for producing these two articles is depicted in FIGURES 10 and 11, the rotor of FIGURE 10 having a constant thread form throughout its circumference and as will be seen in FIGURE 11(a), the section X—X of this thread form for producing the drive screw of FIGURE 9(a) would have ribs 35 separated by relatively deep grooves 36 and each

of the ribs 35 having its crest interrupted by a relatively shallow groove 37 to give the desired degree of sharpness to the rib.

The cross-section X—X of the thread form for producing the article of FIGURE 9(b) is depicted in FIGURE 11(b) and in this case there are ribs 38 separated by grooves 39 and each of the ribs 38 having its crest interrupted by a shallow groove 40 to give the desired degree of sharpening to the crest of the rib.

A further article of spaced-thread type is illustrated in FIGURE 12 together with a view showing the cross-section of the constant thread form which would be provided on a rotor for producing this article.

The article itself is a drive nail having a thread which takes the form of a series of annular ribs 41 separated by annular flat bottom grooves 42 and the cross-sectional form of the rotor for producing such an article would have ribs 43 separated by grooves 44 of asymmetrical cross-section, the crest of each rib 43 being interrupted by a groove 45 to give the desired degree of sharpness.

In addition to the manufacturing advantages with a rotor formed in accordance with the invention as the cross-sectional thread form is uniform throughout the circumference, the rotor can be reversed end-for-end when any appreciable wear has taken place over one side thereof so as to make use of the whole of the circumferential face of the die and thus achieve a further increase in the effective life of the rotor.

By virtue of the uniform thread form on its circumference, manufacture of the rotor is considerably simplified and thus rendered less expensive than a sub-divided rotor and as the blanks can be fed in at close intervals, the machine will give a high output of screws per revolution of the rotor with wear being distributed much more uniformly around the whole circumference of the rotor.

What I claim then is:

1. Dies for the production of spaced thread type screws in a rotary die thread rolling machine of the type wherein blanks are introduced in succession into the space between a rotary die having a thread form around its circumference and a co-operating stationary die of segmental form, said dies comprising a stationary die having on its face which co-operates with the rotary die a thread form comprising alternate ribs and main grooves extending from the starting end to the finishing end of the die, each rib having a sharp form at the starting end and changing gradually from such sharp form to a flat-top form at the finishing end, and a rotary die having around its circumference a thread form comprising alternate ribs and main grooves, each rib having a form, throughout its length, which is similar to the flat-top form at the finishing end of a rib on the stationary die, but each rib on the rotary die having its crest provided with at least one groove running the length of the rib and of depth which is relatively shallow as compared with the depth of the main grooves on the rotary die.

2. Dies for the production of spaced thread type screws in a rotary die thread rolling machine of the type wherein blanks are introduced in succession into the space between a rotary die having a thread form around its circumference and a co-operating stationary die of segmental form, said dies comprising a stationary die having on its face which co-operates with the rotary die a thread form comprising alternate ribs and main grooves extending from the starting end to the finishing end of the die, each rib having a flat top form at the finishing end and at least one groove extending from the starting end of the rib along its length towards the finishing end and gradually decreasing in depth from the starting end until it disappears at a position short of the finishing end of the rib, the depth of such groove at the starting end being relatively shallow as compared with the depth of the main grooves, and a rotary die having around its

circumference a thread form comprising alternate ribs and main grooves, each rib having a form, throughout its length, which is similar to the flat-top form at the finishing end of a rib on the stationary die, but each rib on the rotary die having its crest provided with at least one groove running the length of the rib and of depth which is relatively shallow as compared with the depth of the main grooves on the rotary die.

3. Dies for the production of spaced thread type screws in a rotary die thread rolling machine of the type wherein blanks are introduced in succession into the space between a rotary die having a thread form around its circumference and a co-operating stationary die of segmental form, said dies comprising a stationary die having on its face which co-operates with the rotary die a thread form comprising alternate ribs and main grooves extending from the starting end to the finishing end of the die, each rib having a sharp form at the starting end and changing gradually from such sharp form to a flat-top form at the finishing end, and a rotary die having around its circumference a thread form comprising alter-

nate ribs and main grooves, each rib having a form, throughout its length, which is similar to the flat-top form at the finishing end of a rib on the stationary die, but each rib on the rotary die having its crest provided with at least one groove running the length of the rib and of depth which is relatively shallow as compared with the depth of the main grooves on the rotary die, said rotary die also having a point-forming portion which extends around its circumference and is of constant form throughout its length.
